No. 37,024.

Patented July 5, 1904.

UNITED STATES PATENT OFFICE.

SIDNEY SMITH, OF BRIDGEPORT, CONNECTICUT, ASSIGNOR TO INTERNATIONAL SILVER COMPANY, OF BRIDGEPORT, CONNECTICUT, A CORPORATION.

DESIGN FOR A HANDLE FOR FORKS, SPOONS, OR SIMILAR ARTICLES.

SPECIFICATION forming part of Design No. 37,024, dated July 5, 1904.

Application filed May 27, 1904. Serial No. 210,114. Term of patent 7 years.

To all whom it may concern:

Be it known that I, SIDNEY SMITH, a citizen of the United States, residing at Bridgeport, county of Fairfield, State of Connecticut, have 5 invented a new, original, and ornamental Design for a Handle for Forks, Spoons, or Similar Articles, of which the following is a specification, reference being had to the accompanying drawing, forming part thereof.

10 The drawing is a representation of a fork

embodying my novel design, with the outline of a spoon indicated by dotted lines.

What I claim is—

The ornamental design for a handle for forks, spoons, or similar articles, substantially 15 as herein shown.

SIDNEY SMITH.
